UNITED STATES PATENT OFFICE.

JACOB L. HARING, OF PATERSON, AND HARRY H. STEPHENS, OF GLEN ROCK, NEW JERSEY.

HYDRO-EXTRACTOR.

Application filed May 13, 1925. Serial No. 29,930.

This invention relates to machines of the class in which a rotary element is provided with a cover or guard so as to protect the workmen from said element when in motion. It is applied herein to a centrifugal machine in which the rotary element is a driven element and carries the basket of the machine, such basket being arranged to revolve in a casing and said element projecting upwardly from the casing and the cover or guard for the projecting portion of said element being movable on the casing; this of course is merely illustrative of the invention which may be applied to other than centrifugal machines and the like. The underlying object of the invention is to improve machines of this class by making it impossible to move the cover or guard from the safe to the unsafe or exposing position until the rotary element is either at rest or rotating at a predetermined safely slow speed with the power cut off. Other objects will appear hereinafter.

In the drawings,

Fig. 1 is a side elevation, partly in section, of a centrifugal machine embodying the invention;

Fig. 2 is a fragmentary plan in section on line 2—2, Fig. 1;

Figs. 3 and 4 are sections on lines 3—3 and 4—4, Fig. 2;

Fig. 5 is a side elevation, partly in section on line 5—5, Fig. 6, showing mechanism including one of the cover locks and its controlling means;

Fig. 6 is a plan, partly in section, of said mechanism;

Fig. 7 is a front elevation of the housing appearing in Figs. 5 and 6 and showing in section a certain tongue appearing therein;

Figs 8 and 9 show details of said mechanism;

Fig. 10 is a diagram of the electrical connections; and

Fig. 11 is a sectional detail of a part of the base portion of the machine.

1 is the circular casing or support of a centrifugal machine and 2 is the basket suitably journaled therein on a vertical axis, the axial portion 2' of which protrudes upwardly from the casing and has affixed to its upper end the brake-drum 3 by which, through a clutch or other suitable connection, the basket may be rotated from the

armature shaft 4 of a motor whose fixed casing 5 in the present case is supported by an upright 1' of the casing.

In order to stop the rotation of the basket-including rotary structure a braking means is provided as follows: One end of a brake-band 6 surrounding the brake-drum is secured to a bracket 7 on the upright 1' and its other end is attached to a link 8 extending through a slot 9 in said upright and attached to the arm 10' of a toggle-lever 10 pivoted in the upright and whose other arm 10'' is its handle. When the toggle-lever is moved on its fulcrum from one to the other of the dotted-line and full-line positions of Fig. 2 the toggle action results from the necessity of tensioning the brake-band in order to shift the lever past the dead-center position. In the dotted-line position the link is held bearing against one end of the slot, with the brake set.

The cover or guard for the protruding part of the rotary basket-including structure is a shell 11 in the present instance of visor-like form, or substantially U-shaped in plan, being in its best form shaped substantially like a truncated cone having a portion on one side of its axis removed so that it is open at the truncated end and also at one side. When in closed or guarding position (dotted-lines, Fig. 1) it rests with its edge of greater circumference on the casing and with the edge at the mentioned side thereof abutting against the front vertical face of the upright 1', the motor then protruding above the shell but all the rest of the mentioned basket-including structure being housed within it. It has at its rear upper portion a rearwardly projecting arm 12 carrying at its end a counterbalance weight 13 and fulcrumed between the weight and shell in brackets 14 on upright 1'. When the cover is swung up on its fulcrum the weight encounters the extension 1' as a stop; in this (the open) position the cover or guard exposes to free access the interior of the basket as well as the upwardly protruding part of the rotary structure including the same.

The importance of this construction will be apparent to those familiar with machines of this class: In the first place, when the guard or cover is raised, since as will be apparent the upright 1' is arranged as a

whole offset with respect to a vertical plane flanking the upwardly projecting portion of the rotary structure, clear access to the basket is possible for loading and unloading except for that limited part of its circumference (at the back) where the upright is present; moreover, in its raised position the guard is entirely out of the way, projecting at no point laterally of the machine. When the guard or cover is down the rotary structure is completely housed, insuring entire safety and protection of the contents of the basket. Again, it requires very little effort to move the cover up or down.

15 There are two pivoted catches for the cover which when the cover is in closing or guarding position lock it in that position and require to be individually manipulated in order to release it. One of these is actuated to release the cover by the described means for checking the rotation of the basket-including structure; the other is manually operable subject to the control of the rotating structure itself.

20 25 The first-mentioned catch 15, is pivoted between its ends to the upright 1' (which is hollow, Fig. 2) within the same and has a hook-end protruding therefrom and formed with a cam-surface 15' at said end so that when the cover is closed said surface 15' will ride over a stud 16 on the cover and the catch finally come to rest in locking engagement with said stud (Fig. 4) this end being normally depressed by a spring 17. The other end has a cam-surface 15'' bearing upwardly against the link 8. When the brake is released (full-line position of parts 6-8-10, Fig. 2) the catch is free to lock the cover, but when the brake is tightened to check the rotation of the basket-including structure the link, by wiping over surface 15'', shifts the catch to release the cover.

30 35 40 45 50 55 60 65 As for the other catch: This, 18, is pivoted at 19 between its ends in a housing 20 arranged on the casing, this housing having a hole 21 to receive, when the cover is closed, tongue 22 projecting from the cover, the tongue and the relatively forward end of the catch being adapted to overlap at that time and having their end portions formed with cam-surfaces 22' and 18', respectively, which coact to depress the catch on contact of the tongue therewith, and with hooks 22'' and 18'' which thereupon coact to interlock them and hence lock down the cover. When the cover is thus locked down its release is controlled by the basket-including structure as follows. This structure has a depending axial portion 23 rotating therewith (Fig. 1) which through suitable gearing 24 drives a shaft 25 journaled at its ends in the casings 26 27, and this shaft drives through gearing 28 (Fig. 11) a vertical shaft 29 journaled in casing 27 and the housing 20. The upper end of this shaft (Fig. 8) has fixed thereon

a cylindrical head 29' substantially enlarging said end of the shaft and on which is movable vertically and revolvably a catch-actuator or controller here in the form of a spool 30 whose inwardly projecting stud 31 70 engages in a screw or cam-slot 32 formed in the head 29' of the shaft. The relatively rearward end of catch 18, pressed downwardly by spring 33, overlies and is adapted to be elevated by the lower flange of the actuator when the latter is elevated. The actuator is normally held depressed to the limit afforded by slot 32 by its own weight, and when it is turned in the proper direction and relatively to the shaft it rises, due 80 to its screw-connection with the shaft, so elevating the catch and disengaging the latter from the tongue 22. In the casing 20 in axial alinement with shaft 29 is a stud 34 affording a bearing for a revoluble arm 35 85 which is normally held by a spiral spring 36 with a set-screw 37 bearing against a part 20' of the casing. This arm affords a fulcrum for a grip lever 38 comprising a vertical pin or bearing portion 38^a, an upper or handle arm 38^b protruding through an arcuate slot 20'' in the casing and a lower or grip arm 38^c, which is shod with yielding material 38^d to bear against the periphery of the actuator 30. One end of the spring 36 90 abuts the casing and the other the arm 38^b of lever 38, the spring thus acting to turn the arm 35 and lever 38 each anti-clockwise on its fulcrum. If lever 38 were turned clockwise on its fulcrum (or independently of arm 35) its yielding shoe 38^d would move in against and thus obtain a grip on the barrel of the actuator 30. When therefore the operator grasps the handle arm 38^b of lever 38 and by a quick motion shifts it clockwise 100 toward the remote end of the slot 20'' the result is first to move lever 38 on its fulcrum arm 35, thus to obtain a grip on the actuator, and then shift said lever around the stud 34. This results in turning the actuator if 110 the shaft 29 is stationary or rotating at a sufficiently slow speed (it rotates clockwise in Fig. 6) so that the spool will rise on the shaft due as explained to the screw-connection and consequently shift the catch 18 to releasing position.

115 The energy is admitted to and cut off from the motor by two buttons 39 and 40 arranged in the casing 20 as shown in Figs. 6 and 7, these respectively being opposite and spaced from and adapted to press inwardly the movable circuit controlling parts 41' and 41'' of a circuit controller or switch 41 of known type. The starting button 39 should be rendered inoperative except when the cover is closed. Hence on the block 42 is fulcrumed to move into and out of movement opposing relation to the starting button 39 a lever 43 which is normally held by spring 44 (Fig. 7) in such position and 120

125 130

is adapted to be shifted out of said position by the tongue 22 when the cover is down.

The casing 20 may have a depending extension 45 terminating in an oil well 46, said extension and the well being penetrated by the shaft 29 which is spirally grooved at 29' so as to convey the oil upward for lubricating the shaft. The elevated oil is conveyed 10 through a port 47 against the abutment 29' and through a groove 48 around the shaft and by which it is conveyed to a vertical return passage 49 returning to the oil well.

Operation.—To start the machine the cover 15 must be closed, freeing the starting button, and the brake must be released. The machine is then started by pressing said button. To stop the machine and open the cover it is necessary, after the stopping button 20 is pressed, to perform two separate operations, to wit, to apply the brake, which is necessary in order to release the cover where it is held by the catch 15, and then to spin the actuator 30 relatively to shaft 29 in order to release, as explained, the other catch 18—which may be done with one hand, using the other to lift the cover by grasping its handle 11', Fig. 1. The cover when 25 closed is always held by catch 15 unless the brake is set. Without this it would be possible to close the cover, which would be caught by catch 18, then as an afterthought release the catch by spinning the actuator before the speed of shaft 29 picked up, and then 30 open the cover, leaving the machine running.

A switch 50 may be placed in the starting circuit which is urged by spring 50' (Fig. 10) to break said circuit but is caused by lever 10 to close it when the brake is released. Thus the brake must be released before 40 the motor can be energized.

In Fig. 10 51 is the main circuit containing the motor, with its energy source at 51', and 45 52 is its pivoted switch normally held open by the spring shown and having a solenoid 53 to actuate it. A lead 54 extends from one side of circuit 51 back to the other side thereof (but at the same side of the break in the latter) and contains the solenoid and the contacts 41' and 41'', respectively held normally open and closed by 50 springs as shown. If 41' were closed by the starting button 39 the solenoid will be energized and switch 52 closed. To maintain 55 the solenoid energized and switch 52

closed after release of 41' there is a shunt 54' which leads from the lead 54 between 41' and 41'' to the main circuit and contains the switch 50 and also a switch 55 linked to move with switch 52 and adapted to contact with that part of lead 54 which is between the solenoid and switch 41'. Thus when 41' is closed the shunt is closed through 55 and the solenoid will remain energized until the circuit is broken at 41''. 60 65

It is new in this art to form the cover or guard substantially as shown and described and support it for pivotal movement at its upper rear portion. This has the advantage that it is quite completely out of the 70 way when raised, particularly for loading and unloading the machine.

Having thus fully described our invention what we claim and desire to secure by Letters Patent is:

1. In a centrifugal machine, the combination of a casing open at the top and having an upright thereon, a rotary structure journaled in and projecting above and having a basket in the casing, the upright being arranged substantially as a whole offset with respect to a vertical plane flanking the projecting portion of said structure, and a hollow guard formed substantially U-shaped in plan and resting on the casing with its extremities reaching substantially to said upright, said guard thereby coacting with the upright to surround the projecting portion of said structure but being pivoted to the upright on a horizontal axis near said plane 80 85 and also near the top of the guard and being thereby pivotally movable upwardly to afford clear access to the casing.

2. In a centrifugal machine, the combination of a casing having an upright thereon, 95 a rotary structure journaled in and projecting above and having a basket in the casing, and a hollow guard open at the bottom and resting on the casing and housing the projecting portion of said structure and pivoted to the upright on a horizontal axis near the top of the guard, said guard also having a counterbalance arm extending therefrom past the upright and adapted to abut the same when the guard is moved upward on 100 105 its pivot.

In testimony whereof we affix our signatures.

JACOB L. HARING.
HARRY H. STEPHENS.
